CLAIM

The ornamental design for a rose bouquet pop-up card, as shown and described.

DESCRIPTION

FIG. 1 is a perspective view of a rose bouquet pop-up card showing my new design;

FIG. 2 is a front view thereof;

FIG. 3 is an enlarged view of the portion of the rose bouquet pop-up card depicted in the detail circle of FIG. 2;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The portions shown in broken lines depict environmental subject matter only and do not form any part of the design.
